FEEDING ATTACHMENT FOR POLISHING LATHES

Filed April 8, 1947

UNITED STATES PATENT OFFICE

2,466,082

FEEDING ATTACHMENT FOR POLISHING
LATHESVerley C. Craig and William L. McClenen,
Olympia, Wash.

Application April 8, 1947, Serial No. 740,076

4 Claims. (Cl. 51—74)

1

This invention relates to a feeding attachment for polishing lathes or the like, and more particularly to an attachment adapted for the feeding of strip material, such as molding or the like, past buffer or polishing wheels.

A primary object of this invention is the provision of an improved automatic feeding device for molding or the like adapted to pass the molding to be polished beneath buffer wheels in an improved and expedited manner.

An additional object of the invention is the provision of such a device which will pass the molding in a relatively straight line and hold the same firmly for polishing or buffing.

An additional object of the invention is the provision of such a device which may be readily adapted, substantially automatically, to molding of various widths and thicknesses.

Still another object of the invention is the provision of such a device which will be sturdy and durable in construction, reliable and efficient in operation, and relatively simple and inexpensive to manufacture, assemble, and utilize.

Other objects reside in the combination of elements, arrangements of parts, and features of construction, all as will be more fully pointed out hereinafter and disclosed in the accompanying drawings, wherein there is shown a preferred embodiment of this inventive concept.

In the drawings:

Figure 1 is a top plan view of one form of device embodying features of the instant invention.

Figure 2 is an enlarged sectional view taken substantially along the line 2—2 of Figure 1, a molding being shown in position therein.

Figure 3 is a fragmentary end elevational view showing the driving mechanism for the device.

Figure 4 is a fragmentary side elevational view disclosing the relative position of one of the buffer wheels.

Figure 5 is a fragmentary sectional view similar to Figure 2, but showing an attachment adapted to be utilized with the device in position thereon.

Similar reference characters refer to similar parts throughout the several views of the drawings.

Referring now to the drawings in detail, the device of the instant invention comprises a base 10 of any desired size and suitable material, at one end of which are rotatably mounted a pair of oppositely disposed driving pulleys 11, mounted on vertical axles 12. Secured to the axles 12 are a pair of meshing cogs 13 (see Figure 3), while one of the axles is provided with a bevel gear 14,

2

adapted to mesh with the corresponding bevel gear 15 carried by the drive shaft 16 of an electric driving motor 17. Surrounding each of the pulleys 11 is a portion of a flexible steel feed belt 18. The opposite end of each feed belt 18 is rotatably mounted about one of a pair of idler pulleys 19, each of which is mounted on an axle 20.

It will now be seen that rotation of either of axles 12 by the associated motor will cause corresponding rotation of each pulley 11 through the medium of the gears 13, and that such movement will occasion rotation of the pulleys and their associated belts 18 in opposite directions, as indicated by the arrows in Figure 1, in such manner that the adjacent faces of each belt are moved in the same direction to feed therethrough any article passed therebetween.

Positioned on either side of the intermediate section of each belt 18 are a pair of oppositely disposed pressure bars 25, each provided with a longitudinally extending recess throughout the entire length thereof, in which are journaled for rotation rollers 26 serving as bearings for the belts 18. The opposite pressure bars 25 are connected by a plurality of transversely extending rods 27, each extending outwardly a substantial distance beyond the sides of the pressure bars, and each provided at its opposite ends with compression springs 28 secured in position, as by cotter pins 29, the arrangement being such as to bias the pressure bars 25 towards each other.

As best shown in Figure 2, the upper surface of each pressure bar 25 is substantially flush with the top of its associated belt 18, and beveled inwardly, as indicated at 30, to provide a relatively narrow supporting surface for a molding 31, or the like, adapted to be passed between the belts 18.

In the use of the device, the assembly is adapted to be positioned beneath a series of longitudinally aligned buffer wheels, one of which is indicated at 35, each of which is mounted on a drive shaft 36 adapted to be rotated, as by means of an electric motor 37, or the like.

In the operation of the device, it will be readily understood that a molding 31 is adapted to be fed between the belts 18 from the end of the device, whereupon it is grasped by the oppositely disposed belts 18 and held firmly by virtue of the bias of springs 28 and the pressure bars 25. The molding 31, or the like, is then passed beneath the buffer wheels 35, and when passed from the device at the opposite end thereof, is completely polished.

Various shapes and sizes of moldings or the like may be readily utilized with the device, and, under those circumstances where molding an exceptionally wide top surface, such as 31a (see Figure 5) is utilized, triangular strips 14 are adapted to be secured to the beveled faces 13 of pressure bars 25 in any desired manner, as by nails 41, or the like, and extend substantially along the entire length thereof, for the purpose of providing added support for the wider molding.

From the foregoing, it will now be seen that there is herein provided a device which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

We claim:

1. In a device of the character described, a base, a pair of driven pulleys at one end of said base, a pair of idler pulleys at the other end of said base, a pair of belts extending in parallel relation between idler and driven pulleys, means for simultaneously rotating the driven pulleys in opposite directions to move the adjacent inner sides of the belts simultaneously in one direction, pressure bars positioned oppositely inwardly of adjacent sides of the belts to bias said adjacent sides towards each other, rollers carried by each pressure bar serving as bearings for the belts, and spring means carried by said pressure bars biasing said bars towards each other.

2. In a device of the character described, a base, a pair of driven pulleys at one end of said base, a pair of idler pulleys at the other end of said base, a pair of belts extending in parallel relation between idler and driven pulleys, means for simultaneously rotating the driven pulleys in opposite directions to move the adjacent inner sides of the belts simultaneously in one direction, pressure bars positioned oppositely inwardly of adjacent sides of the belts to bias said adjacent sides towards each other, rollers carried by each pressure bar serving as bearings for the belts, and spring means biasing said bars towards each other, said last-mentioned means including rods extending transversely through the pressure bars and beyond, cotter pins in the extremities of the rods and compression springs positioned between the cotter pins and their adjacent pressure bars.

3. In a strip polishing machine comprising a base and a motor-driven buffer supported on said base, strip-feeding means comprising a pair

of driven pulleys rotatably mounted in side-by-side relationship on said base adjacent one end thereof, a pair of idler pulleys rotatably mounted in side-by-side relationship on said base adjacent the opposite end thereof, a pair of flat, endless belts each surrounding a respective driven pulley and the opposite idler pulley, the inner portions of said belts being disposed in spaced-apart, substantially parallel relationship longitudinally of said base, a pair of pressure bars disposed one at the outer side of the inner portion of each belt and extending between the corresponding driven and idler pulleys, means driving said driven pulleys in opposite directions to move the inner portions of said belts in the same direction longitudinally of said base, and spring means carried by and operatively connecting said pressure bars to resiliently urge the inner portions of said belts toward each other to clamp a strip therebetween.

4. In a strip polishing machine comprising a base and a motor-driven buffer supported on said base, strip-feeding means comprising a pair of driven pulleys rotatably mounted in side-by-side relationship on said base adjacent one end thereof, a pair of idler pulleys rotatably mounted in side-by-side relationship on said base adjacent the opposite end thereof, a pair of flat, endless belts each surrounding a respective driven pulley and the opposite idler pulley, the inner portions of said belts being disposed in spaced-apart, substantially parallel relationship longitudinally of said base, a pair of pressure bars disposed one at the outer side of the inner portion of each belt and extending between the corresponding driven and idler pulleys, means driving said driven pulleys in opposite directions to move the inner portions of said belts in the same direction longitudinally of said base, spring means carried by and operatively connecting said pressure bars to resiliently urge the inner portions of said belts toward each other into strip-clamping relationship, and a plurality of spaced-apart, anti-friction rollers carried by each pressure bar and bearing against the outer sides of the inner portions of the corresponding belts.
